UNITED STATES PATENT OFFICE

RUDOLPH J. SCHWARZ, OF PROVIDENCE, RHODE ISLAND, ASSIGNOR TO AMERICAN STANDARD WATCHCASE COMPANY, OF PROVIDENCE, RHODE ISLAND

METHOD OF MAKING WATCH CENTERS

Application filed December 31, 1928. Serial No. 329,594.

This invention relates to method of making watch centers and the primary object thereof is to provide a method of making watch centers wherein same are integral with the hollow or tubular bearing through which the winding arbor extends, thereby not only providing a stronger structure but also one which dispenses with the usual custom of soldering the bearing onto the center.

10 The invention further aims to provide a method which can be easily, and quickly and economically practiced.

In the drawings,

Figure 1 is a plan view of the blank;

15 Figure 2 is an end elevation thereof;

Figure 3 is a plan view of the blank in the second stage of the method;

Figure 4 is an end elevation of Figure 3;

20 Figure 5 is a plan view of the complete center;

Figure 6 is an end view of Figure 5 and

25 Figure 7 is an enlarged section on line 7—7 of Figure 5.

In proceeding in accordance with the present invention a blank 1, as shown in Figures 1 and 2 is employed, and which has an open center and a boss 2, integral therewith and extending radially from the periphery of the blank. The boss is formed with a prick

30 punch 3 which latter is located to one side of the center of the boss, as shown in Figure 2. The boss as shown in Figures 3 and 4, is next

35 turned down into cylindrical form, and has a hole 4 drilled therethrough at the point of the prick punch, the blank being also partially

35 trimmed so as to have its surfaces and edges smooth and polished. The final step of the method resides in forming a circular channel 5 on the boss intermediate its ends, and in

40 forming the bezel-receiving channel 6 in a face of the blank and the slit 7. This slit is for the purpose of receiving a knife or other sharp instrument so as to enable the center to be engaged and moved out of the case, the

45 latter not shown.

It should be distinctly understood that the shape of the center can be varied, as desired, to provide for square, rectangular, oval, hexagonal, or other shapes, and that the slitting

50 and bezel attaching means may be varied,

according to the nature of the bezel, which latter in some instances have bracelet or strap engaging or holding loops or other means.

From the foregoing it will be seen that the boss which forms the winding arbor bearing 55 is integral with the center and provides a stronger and more durable structure, which is of increased anchorage as compared to soldered bearings as usual in the art.

Having thus described my invention what I claim as new and desire to secure by Letters Patent is:—

1. The herein described method of making watch centers which resides in providing a blank having the general shape of the center 65 and which has an integral boss extending radially from the periphery thereof, then in drilling the boss and in turning the exterior thereof to provide a tubular cylindrical bearing for the winding stem or arbor, and in forming a circular groove on the periphery of the boss between its ends, and finally in shaping the blank into final form and in providing same with bezel receiving means.

2. The herein described method of making 75 watch centers which resides in providing a blank having an integral boss, then in partially shaping the blank and in forming the boss into tubular cylindrical shape to form a winding arbor bearing and finally in finishing 80 the blank and providing same with bezel engaging means.

3. The herein described method of making watch centers which resides in providing a blank having an integral boss, then in forming 85 the boss to provide a tubular winding arbor bearing, and finally in finishing the blank and in providing same with bezel engaging means.

In testimony whereof I have hereunto 90 signed my name.

RUDOLPH J. SCHWARZ.
